UNITED STATES PATENT OFFICE.

CHARLES E. TROWBRIDGE, OF WHITINSVILLE, MASSACHUSETTS, ASSIGNOR
TO THE WHITINSVILLE SPINNING RING CO., OF SAME PLACE.

DESIGN FOR A SPINNING-RING.

SPECIFICATION forming part of Design No. 20,538, dated March 3, 1891.

Application filed October 25, 1890. Serial No. 369,362. Term of patent 14 years.

To all whom it may concern:

Be it known that I, CHARLES E. TROWBRIDGE, residing at Whitinsville, in the county of Worcester, State of Massachusetts, have 5 invented and produced a new and original Design for a Spinning-Ring, of which the following is a specification, reference being had to the accompanying drawings, forming part thereof.

10 Figure 1 shows in plan view a spinning-ring, showing my design; Fig. 2 a partial sectional view of the same.

The leading feature of my design consists 15 in an annular rounded rib rising a short distance from a plane surface midway between the upper and lower flanges of the spinning-ring upon the outside or inside, or both, and of a less diameter than that of the upper and lower flanges.

20 a represents the ring having upper and lower circumferential flanges $a' a'$. The ring has an annular rib a^2 on it exteriorly midway between the upper and lower flanges $a' a'$,

said rib a^2 projecting from a plane face, and said ring has an annular rib a^3 on it interiorly 25 between the upper and lower flanges $a' a'$, said rib a^3 rising from a plane face, the ribs $a^2 a^3$ being rounded, as shown in Fig. 2. It will be noticed that the annular ribs $a^2 a^3$ extend beyond the plane part of the ring for a 30 less distance than the flanges above and below them and that they are located between the flanges and wholly within the circle occupied by the flanges and are rounded in cross-section.

35 I claim—

The design for a spinning-ring, substantially as herein shown and described.

In testimony whereof I have signed my name to this specification in the presence of 40 two subscribing witnesses.

CHARLES E. TROWBRIDGE.
